TAPE DISPENSER

Raymond W. Hazuka, West St. Paul, and Dorman N. Thompson, North St. Paul, Minn., assignors to Minnesota Mining and Manufacturing Company, St. Paul, Minn.

Filed Feb. 4, 1970, Ser. No. 21,262

Term of patent 14 years

Int. Cl. D19—02

U.S. Cl. D74—1

FIG. 4

FIG. 2

FIG. 1

FIG. 3

FIG. 5

FIG. 6

FIG. 1 is a side elevational view of the tape dispenser of this invention, the other side being identical to the side illustrated;

FIG. 2 is an end elevational view of the tape dispenser of FIG. 1, viewed from the left thereof;

FIG. 3 is an end elevational view of the tape dispenser of FIG. 1, viewed from the right thereof;

FIG. 4 is a top plan view of the tape dispenser of FIG. 1;

FIG. 5 is a bottom plan view of the tape dispenser of FIG. 1; and

FIG. 6 is a perspective view of the tape dispenser showing our new design.

We claim:

The ornamental design for a tape dispenser, as shown and described.
